UNITED STATES PATENT OFFICE.

EDITH DAYTON TITSWORTH, OF GREENWICH, CONNECTICUT.

DESIGN FOR A CHARACTER-DOLL.

45,244.

Specification for Design.

Patented Feb. 10, 1914.

Application filed December 9, 1913. Serial No. 805,651. Term of patent 7 years.

To all whom it may concern:

Be it known that I, EDITH DAYTON TITSWORTH, a citizen of the United States, residing at Greenwich, Fairfield county, Connecticut, have invented a new, original, and ornamental Design for Character-Dolls, of which the following is a specification, reference being had to the accompanying drawings, forming a part thereof, and in which—rear view of a character doll, showing my new design.

I claim

The ornamental design for a character doll as shown.

EDITH DAYTON TITSWORTH.
